UNITED STATES PATENT OFFICE.

CHARLES JOHN COOKE, OF HONGKONG, CHINA.

AEROPLANE-GUN.

1,294,240.

Specification of Letters Patent. Patented Feb. 11, 1919.

Application filed February 11, 1918. Serial No. 216,673.

To all whom it may concern:

Be it known that I, CHARLES JOHN COOKE, a resident of Hongkong, China, and a subject of the King of the United Kingdom of 5 Great Britain and Ireland, have invented certain new and useful Improvements in Aeroplane-Guns; and I do hereby declare the following to be a full, clear, and exact 10 description of the invention, such as will enable others skilled in the art to which it appertains to make and use the same.

The invention relates to improvements in ordnance or relatively heavy guns for aeroplanes, and has for its object to so coördinate a gun of the non-recoil type, open at 15 both ends and adapted to fire a charge including a projectile, an explosive and a reaction mass, with an aeroplane, so that the gun when fired will occupy a position with 20 its longitudinal axis parallel with the longitudinal axis of the aeroplane, whereby the laying or training of the gun on the target will be effected by so maneuvering the aeroplane that the longitudinal axis of the latter 25 is in direct line with the target. The essential advantages of such a coördination are first, that the gun may be trained directly upon the target, if the latter is another aeroplane or an elevated object by maneuvering 30 the plane to bring its longitudinal axis in direct line with the target, so as to insure accuracy of fire with relatively large projectiles, and second, by causing the plane to nose-dive vertically above and toward the 35 target, when the latter is below the plane, and thereby obviate the necessity of allowing for the speed of the aeroplane, or other necessary corrections, as when the aeroplane is moving in any other direction than the 40 vertical, with respect to the target. To these ends the gun is mounted outside of the fuselage of the aeroplane with its longitudinal axis normally parallel with the longitudinal axis of the plane, and is preferably swiveled 45 or pivoted below or at one side of the fuselage so that the blast from the rear of the machine, and at the same time permitting the rear end of the gun to be tilted toward the 50 fuselage to admit of the charge being loaded into the rear end of the gun with facility and despatch, means being provided to tilt the rear end of the gun toward the fuselage

in the loading operation and to retain the gun rigidly in axial alinement with the axis 55 of the plane when the gun is ready to be fired. In order to facilitate the proper aiming of the gun and to indicate to the gunner when it is properly trained on the target, there is preferably mounted on the aeroplane 60 an auxiliary gun of small caliber preferably adapted to fire tracer projectiles, said auxiliary gun also being normally parallel with the longitudinal axes of the aeroplane and main gun. When the gun is employed with 65 an aeroplane of the tractor type, it is preferable to provide firing mechanism which will admit of the gun being fired only at times when the propeller blades are out of the line of fire. These and other objects of 70 the invention will be more particularly described in the annexed specification, in connection with the accompanying drawings, in which,

Figure 1 is a side elevation partly in section of a tractor biplane including the non-recoil gun and its accessories. 75

Fig. 2 is an enlarged partial sectional view of the aeroplane and gun.

Fig. 3 is a front elevation partly in section 80 of the apparatus.

Fig. 4 is a fragmentary sectional elevation of the gun and charge, and

Fig. 5 is a further fragmentary sectional detail view of the gun and its charge. 85

Referring to the drawings, 1 indicates the body or fuselage of an aeroplane of the biplane type having the propeller 2 mounted at the forward end on the crank-shaft 2' of the engine, as is usual in machines of this 90 type.

Mounted rigidly on the machine with its axis parallel with the longitudinal axis of the machine is a machine gun 3, which may be employed to fire ordinary ammunition 95 and which is adapted to use smoked bullets or tracer projectiles to indicate the effectiveness of the aim and to show definitely when the aeroplane is in position to cause the machine gun projectiles to find the target. Said machine gun 3 may be any of the well known types adapted to be held or locked rigidly with its barrel parallel with the longitudinal axis of the machine so that the gun 100 is aimed by maneuvering the machine. 105

The main gun 5 is of the so-called non-

recoil type, involving a rifled barrel open at both ends and adapted to receive a charge including the projectile proper, such as 11, an intermediate chamber 12 carrying an explosive and a reaction mass 13 to the rear of the explosive chamber, which mass may comprise either a solid weight or a body of loose material, such for example, as bird shot, which reaction mass has a definite weight 10 with respect to the weight of the projectile so that the inertia of the projectile and the reaction mass will be practically identical when the propelling charge is fired and no shock or jar will be imparted to the gun or 15 to the aeroplane.

The gun 5 is mounted exteriorly of the fuselage and in such relation thereto that the blast from the rear end of the gun when the latter is fired will not strike any part of 20 the machine, but will pass harmlessly to the rear of the machine.

Preferably, the gun 5 is mounted on trunnions 6 in pendent brackets or bearings 7 attached to the under side of the fuselage so 25 that the rear end of the gun may be tilted upward to facilitate loading. Obviously, however, the gun may be similarly mounted on either side of the fuselage provided that it is so arranged that no part of the aero- 30 plane structure will be in the line of fire, either of the projectile or the reaction mass. In the form of the apparatus illustrated, the rear end of the gun is provided with a pivoted link 8, which is connected to the under 35 side of a swinging trap 9 mounted in the bottom of the fuselage and adapted to swing upward and forward, and thereby tilt the rear end of the gun upward so that it occupies an inclined position, indicated in dotted lines, with the rear muzzle extending 40 into the body of the fuselage in position to enable the charge to be loaded directly into the gun by the operator. When the trap is closed, the gun is swung to its normal position, 45 with its longitudinal axis parallel with that of the body of the machine and is rigidly held in this position by the link 8. The trap is provided with a lifting handle 10 and may, if desired, also be furnished with 50 a suitable locking bolt to hold it rigidly in position, no matter what the position of the aeroplane may be.

When the gun 5 is mounted in the position shown, so as to fire toward the front of 55 the machine, it is desirable that means be provided to permit the gun to be fired only when the blades of the propeller are out of the line of fire, and to this end, the electrical firing circuit usually employed by guns 60 of this character is provided with a synchronizing circuit closer operated from the engine shaft, which admits of the gun being fired, by closing the normal firing switch, only when the propeller blades have moved 65 out of the line of fire. The firing of the cir-

cuit includes a plug 20, preferably of the character shown in a copending application, Serial No. 191,772, filed September 17, 1917, adapted to make contact with circuit accessories carried by the charge, and an external circuit including conductor 21, battery 22, firing switch or key 23, a brush 24 in engagement with an insulating sleeve 25, carried by the end of the engine crank shaft 2' and provided with contacts 26 connected 75 to the crank shaft 2', a brush 27 in engagement with said crank shaft and a circuit lead 28 connected to the barrel of the gun. The contacts 26 are so located with respect to the brush 24 that the circuit from the battery 22 to the explosive charge can only be completed when the blades of the propeller 2 are out of the line of fire, as will be understood.

From the foregoing description, it will be 85 apparent that the gun 5 may be made of any desired size and caliber, compatible with the carrying capacity of the aeroplane, and said gun may be constructed to either discharge a shell or projectile at high velocity, 90 or at relatively low velocity, the latter being determined by the relative weights of the projectile and the reaction mass and the relative lengths of the fore and aft sections of the gun barrel through which the projectile and the reaction mass respectively travel during the firing operation. For general service, such as fighting other aeroplanes, dirigibles, observation balloons, elevated targets, as well as for attacking 95 places, positions or objects on the land or sea below the aeroplane, it is desirable that the gun be constructed and arranged to develop a fairly high initial velocity of the projectile, and a convenient arrangement 100 with this end in view, will be to provide the gun with a length of barrel at the projectile end substantially half the length of the barrel at the reaction mass end and to make the projectile substantially twice the 105 weight of the reaction mass.

In operating the machine against hostile aeroplanes, balloons, or other elevated objects, the plane is directed toward the object and the range of the latter determined 115 by means of the auxiliary machine gun 3, which, as indicated, may be supplied with smoked bullets or other forms of tracer projectiles which will indicate when the machine gun is trained directly on the object so that the hits may be accurately observed. With the main gun 5 loaded and the foregoing conditions established, the gunner presses the firing key 23 and as soon as a conductor segment 26 passes under brush 24, the firing circuit is completed and the charge exploded, thereby driving the projectile 11 out of the forward end of the gun and expelling the reaction mass 13 from the rear 120 of the gun, as will be understood. For this 125 130

particular mode of attack, the projectile may take the form of shrapnel shell, high explosive shell, or, if desired, a solid shot, any one of which would be effective to demolish a hostile machine in the air.

In order to prevent the rearward displacement of a charge in the gun 5, when the aeroplane is climbing and the longitudinal axis of the gun is inclined downwardly to the rear, means, such as illustrated in Figs. 4 and 5, may be provided for yieldingly retaining the charge in the gun barrel, which means, while capable of holding the charge firmly in place, will, nevertheless, give way when the charge is fired without imposing any material stress or resistance on the mechanism. Two forms of retaining means are shown, one comprising a spring-pressed plunger 20' mounted in the firing plug 20 and engaging a shallow circumferential groove 15 in the contact ring 14 carried by the reaction mass 13. The other means comprising a series of spring metal pawls or detents 16, mounted circumferentially of the reaction mass 13 in recesses 17, with their free ends engaging the beveled ends 19 of the rifling ribs in the rear part of the gun barrel and occupying a circumferential recess 18 in the bore of the gun. When the charge is fired the initial movement of the reaction mass 13 causes plunger 20' to disengage groove 15 and the ends of detents 16 ride up inclines 19 and rest upon the surfaces of the rifling ribs. Of course, any other suitable retaining means may be employed to hold the charge in position provided the same is capable of yielding or suspending its holding function without imposing material stresses on the gun and the aeroplane.

40 A particularly efficacious mode of operating the apparatus, however, depends on the feasibility of maneuvering the aeroplane so as to bring it directly above the target, with the axis of the aeroplane vertical, by means of the so-called nose-dive. With the aeroplane flying at a height of several thousand feet, it will be obvious that the nose-dive may be prolonged for a sufficient time to insure an absolutely accurate laying of the gun 5 directly on the target, and when this is accomplished, the gun may be fired practically instantly by pressing the firing key 23. The particular advantage of this mode of attack is that, because of the fact that the aeroplane is moving downwardly and toward the target in a vertical direction above the same, no allowance has to be made for the speed of the aeroplane, nor for its height above the target, and moreover, the vertically downward velocity of the aeroplane itself will be added to that of the explosive charge as applied to the projectile to increase the force of impact of the latter, the advantages of which are obvious.

65 With the heavier types of aeroplanes em-

ployed, it will be apparent that the gun 5 may be made sufficiently large to carry heavy explosive bombs, as well as shells and other forms of projectiles, and when so employed, the projectiles whether in the form of bombs or shells, may be fired with great accuracy. It will be understood, of course, that as soon as the gun 5 has been fired, the aeroplane will immediately abandon the nose-dive and turn off in horizontal flight to circle and climb to either escape, or, if necessary, repeat the attack.

What I claim is:

1. The combination with an aeroplane, of a non-recoil gun open at both ends and adapted to fire a charge including a projectile, an explosive and a reaction mass, the gun being mounted exterior of the fuselage and having its longitudinal axis normally parallel with the axis of the aeroplane. 85

2. The combination with an aeroplane, of a non-recoil gun open at both ends and adapted to fire a charge including a projectile, an explosive and a reaction mass, the gun being pivotally mounted exterior of the fuselage and having its longitudinal axis normally parallel with the axis of the aeroplane. 90

3. The combination with an aeroplane, of a non-recoil gun open at both ends and adapted to fire a charge including a projectile, an explosive and a reaction mass, the gun being pivotally mounted exterior of the fuselage and having its longitudinal axis normally parallel with the axis of the aeroplane, and means to tilt the gun to inclined 100 position for loading. 95

4. The combination with an aeroplane, of a non-recoil gun open at both ends and adapted to fire a charge including a projectile, an explosive and a reaction mass, the gun being mounted on trunnions below the fuselage and normally in axial parallelism with the longitudinal axis of the aeroplane. 105

5. The combination with an aeroplane, of a non-recoil gun open at both ends and adapted to fire a charge including a projectile, an explosive and a reaction mass, the gun being mounted exterior of the fuselage and having its longitudinal axis normally 115 parallel with the axis of the aeroplane, a swinging support for the rear of the gun, and means to operate said support to tilt the gun into loading position.

6. The combination with an aeroplane, of a non-recoil gun open at both ends and adapted to fire a charge including a projectile, an explosive and a reaction mass, the gun being mounted exterior of the fuselage and having its longitudinal axis normally 125 parallel with the axis of the aeroplane, a swinging trap in the bottom of the fuselage, and a link connecting the trap with the rear of the gun, whereby the gun is tilted to loading position when the trap is raised. 130

7. The combination with an aeroplane, of a non-recoil gun open at both ends and adapted to fire a charge including a projectile, an explosive and a reaction mass, the gun being mounted exterior of the fuselage and having its longitudinal axis normally parallel with the axis of the aeroplane, and an auxiliary tracer gun mounted on the aeroplane with its axis parallel to the longitudinal axis of the machine.

8. The combination with an aeroplane, of a non-recoil gun open at both ends and adapted to fire a charge including a projectile, an explosive and a reaction mass, the gun being mounted exterior of the fuselage and having its longitudinal axis normally parallel with the axis of the aeroplane, and

means for yieldingly locking the charge in the gun.

9. The combination with an aeroplane, of 20 a non-recoil gun open at both ends and adapted to fire a charge including a projectile, an explosive and a reaction mass, the gun being mounted below the fuselage of the aeroplane and having its longitudinal 25 axis normally parallel with the axis of the fuselage.

In testimony whereof I affix my signature, in presence of two subscribing witnesses.

CHARLES JOHN COOKE.
